United States Patent Office

Des. 196,958
Patented Nov. 26, 1963

196,958

INDUSTRIAL CLEANING MACHINE

Elvin R. Goodrich, 400 W. Odom Road,
Oklahoma City, Okla.

Filed May 25, 1962, Ser. No. 70,281

Term of patent 14 years

(Cl. D9—2)

FIG. 1.

FIG. 2.

FIG. 3.

FIG. 4.

FIG. 5.

FIGURE 1 is a top plan view of an industrial cleaning machine, showing my new design;

FIGURE 2 is an elevational view of one side of the machine;

FIGURE 3 is an elevational view of the other side of the machine;

FIGURE 4 is an elevational view of one end of the machine; and

FIGURE 5 is an elevational view of the other end of the machine.

I claim:

The ornamental design for an industrial cleaning machine, as shown.
